UNITED STATES PATENT OFFICE.

FREDERICK ALFRED WILSON, OF LONDON, ENGLAND.

APPARATUS FOR THE MANUFACTURE OF ROOFING TILES.

Application filed July 27, 1926, Serial No. 125,121, and in Great Britain July 27, 1925.

This invention relates to roofing tiles and more particularly to tiles of the kind known as cement tiles, made from a semi-plastic mixture of cementitious materials, adapted to dry and harden without the application of heat.

The invention has for its principal object to provide for molding roofing tiles in lengths comprising a plurality of tiles, each length of tiling being divided up into sections before removal from the mold.

The invention has also for its object to provide an improved construction of molding plate or pallet, which in addition to forming the bottom of the mold, comprises also the ends of the latter.

A further object of the invention is to cause the semi-plastic mixture to settle down in the mold, by the application of a jiggling motion which lifts the opposite ends of the mold alternately with intervening pauses or dwells.

The invention also includes certain constructional features and arrangements as hereafter set forth.

I attain the above mentioned objects by the mechanism illustrated in the accompanying drawings, in which:

Figures 1 and 2 represent my improved tile molding machine, in plan and in elevation respectively.

Figure 3 is a fragmentary view in section on line 3—3 of Figure 1 and on a larger scale.

Figure 4 is a transverse section of the molding machine on line 4—4 of Figure 1, also on a larger scale.

Figure 5 is an end view of Figure 1, seen from the right, also on a larger scale.

Figure 6 is a diagram explanatory of the use of a color box for carrying the knives by which the lengths of molded tiling are divided up into sections.

Figure 7 is a side elevation of the preferred form of color box with the dividing knives secured thereto.

Figure 8 is a similar view of a modification hereafter described.

Figure 9 is a detail in cross section of a pallet plate with transverse ribs formed integral therewith.

Figure 10 represents a stack of pallets as arranged for drying the molded tiles.

Referring particularly to Figures 1 and 2, the machine comprises a support in the form of an open-topped table A having legs A¹ and longitudinal members A², the latter being

connected together by cross members g, which carry the weight of the mold. Each machine requires a number of pallets or molding plates, for example four to six thousand depending upon the output of tiles and upon the length of time required for drying.

The pallets or molding plates a are of stamped metal, of width corresponding to the length of a single tile, and of length sufficient to accommodate a convenient number of tiles laid side by side; in the drawings the length of the pallet corresponds to the width of six single tiles. The plate a may be curved transversely as shown in Figure 4, its under surface being provided with shallow impressions to form on the upper side corresponding raised portions b which produce the customary hollows in the backs of the molded tiles.

One of the longitudinal edges of the plate a is provided at intervals with cranked flanges a¹ to form an interrupted rebate or channel c for molding the customary lip or projection by which the tiles are mounted in place on a roof; the interruptions c¹ correspond with the lines of division between the individual tiles in the mold, so that the dividing knives (as described later) make clean cuts through the length of tiling to separate one tile from another.

At the ends of the pattern plate a and also if desired at the center, there are provided raised guide surfaces d d and d¹, which may, for example, consist of transverse bars secured in place as shown by bolts d². These guide surfaces are curved similarly to the transverse section of the plate, and their height corresponds with the thickness of the molded tiles; they act to support the striker by which the material is struck off after filling the mold and serve to stiffen the plate transversely and prevent buckling under load.

In addition the end bars d form closures for the ends of the mold, making it unnecessary to provide fixed ends for that purpose. The central transverse bar d¹, when used, serves also to divide up the molded tiling into two halves, thereby reducing the labor of cutting by knives.

The molding plate a is preferably constructed as a steel pressing, for example of 16 or 18 gauge; the raised guide surfaces d d¹ may be pressed integral with the molding surface as shown in Figure 9, instead of being attached as described above, a wearing strip d³ being provided if desired. The plate a is

longitudinally reinforced by stiffening angle bars n parallel to the edges, as well as by the cranked flange a^1 .

The pallets or molding plates are adapted 5 to be inserted between two parallel rails such as angle-irons $e e$, which are suitably framed together as by cross-braces $f f^1$, with their extremities f^2 riveted to the rails e . The top edge of each of the side rails $e e$ conforms 10 with the raised surfaces $d d^1$ of the molding plate a , the latter with its raised surfaces $d d^1$ and the fixed longitudinal rails e together forming an open mold.

In one of the rails e there are inserted pegs 15 k (see Figure 4) which pass upwards through holes k^1 in the molding plate a to form the usual holes required in roofing tiles for nailing down; the flanged edge a^1 of the plate rests upon the horizontal portions of these 20 pegs k . Upon the other rail e there are provided horizontal studs s upon which the opposite edge of the plate rests, this edge being fitted with the stiffening angle-bar n previously mentioned.

25 Beneath the raised guide surfaces d at the ends of the plate a there are fitted blocks o , for example of wood, which are adapted to locate the pallet plates in correct position longitudinally. In placing the pallet between 30 the guide rails, the wood blocks o are fitted over and outside the end cross braces f^1 of the frame, the inward sides of the blocks o being tapered as seen in Figure 3 in order to draw the parts into correct position. When 35 the tiles have been molded and the plate a is removed for the drying or hardening of the tiles, as hereafter explained, the wood blocks o enable the plates to be stacked upon one another (see Figure 10) with a suitable 40 air space above the molded tiles; for this purpose the under surfaces of the wood blocks may be curved concavely to agree with the curvature of the underlying molding plate.

As shown, these wood blocks o have parts 45 cut away as at x Figure 5, to form hand holes for facilitating the lifting of the pallet plates. They may also be provided with socket-holes o^1 (see Figure 5) in their lower faces, the ends of the plates a being fitted with projections, for example nuts p , at corresponding 50 positions, in order to secure the stacked pallets against movement during transfer, drying or hardening.

The frame composed of the rails e and their 55 cross-braces $f f^1$ resting on the cross bars g of the open-topped table A, may be subjected to a vibratory jiggling action with the object of consolidating the cementitious matter in the mold and settling it into the corners and 60 edges. For this purpose, I have illustrated a cam shaft h extending along the table beneath the mold, the shaft being driven by any convenient means such as belt pulleys h^1 and carrying a pair of cams $i i^1$ which engage tappets j secured to the lower sides of the end

cross-braces f^1 . In the cross bars g nearest to the cams there are mounted steady-pegs g^1 which pass through clearance holes e^1 in the rails $e e$; these pegs g^1 serve as guides for the frame during its jiggling movements. The 70 cams are preferably provided each with two spiral rises, the diameter corresponding to the full lift of one cam being set at ninety degrees relatively to that of the other cam; the opposite ends of the mold are therefore 75 raised alternately at equal intervals, with four lifts in each revolution of the cam shaft. The amount of rise and fall of the ends of the frame may be about one-third of the lift 80 of the cams; thus the frame and mold do not fall on to the contour of the cam, but are arrested by the cross bars g of the table. Further, between the fall of one end of the frame and the rise of the other end, there will be an 85 interval or period of rest, resulting in an even action throughout the entire mold, of which the center part is lifted twice as often as the ends but only to one half the height.

In addition to the jiggling action, ramming or tamping can be carried out by hand or otherwise before the material in the mold is leveled off by means of a strickle or straight edge in the well known way. The surplus material thus removed can be caught by a 90 pan y mounted in the lower part of the table, 95 from which pan the operator takes the material for filling the mold.

I also provide knives for dividing up the 100 length of tiling into sections or single units of the desired width; these knives are preferably mounted upon the color-box usually employed for coating the tiles with the desired coloring matter. As shown in Figures 6 and 7, the color-box l is provided on its lower face with the requisite number of 105 knives m for dividing up the lengths of molded tiling, the color-box sliding transversely across the mold, as indicated by the arrow in Figure 6; the edges of the knives m are curved to agree with the section of the plate a , and the tops of the rails e are notched as at m^1 at the points where the knives pass through them. As the color-box is brought 110 across the mold, the leading point of the knife cuts completely through the thickness of the tiling, the color-box being guided over the curved pallet for example by rollers e^2 in conjunction with similarly curved guide rails l^2 , and a tail rod l^3 in conjunction with a fixed roller l^4 . The color-box has the usual wire 115 gauze q at its base, through which the color can be worked by hand upon the molded tiles, a tray z being provided to prevent waste of color when the box is returned to its initial 120 position.

The pallet or molding plate a with the 125 completely formed tiles is then removed and stacked upon the previously-filled plates a as shown in Figure 10, so that the drying, hardening by air or steam, or other treatment 130

of the tiles can be effected, the plates *a* thus taking the place of the customary drying racks and obviating the necessity for molding each tile or pair of tiles separately and then transferring it to a drying rack, fixed or movable. As already stated, the wood blocks *o* supporting the stacked plates with intermediate air spaces above the molded tiles, secure the plates against movement by the engagement of their socket-holes *o*¹ with the projections *p* upon the underlying plates.

When sufficiently dried or hardened, the tiles are removed from the plate and stacked for maturing.

The number of tiles molded at each operation may be varied by employing molding plates of different length, or by altering the number and position of the cutting blades. For example, instead of forming six tiles of standard width, the same pattern plate may be used to form four closing tiles each of width equal to one-and-a-half ordinary tiles, by substituting an alternative cutting device with one blade *m* at the middle of each half of the plate, as illustrated in Figure 8. This figure likewise illustrates a double cutting blade *t t'* at the center of the underside of the color-box, such double blade being intended to cut out a narrow transverse strip from the middle of the length of tiling, and rendering the provision of the central raised surface *d*¹ unnecessary. The removal of the central cut-out strip also facilitates the lifting of the tile sections from the mold.

The invention is not limited to the manufacture of cement tiles, but may be applied to the production of clay tiles and the like, in which case the molded tiles after drying may be burned in a kiln of any suitable type.

Having thus described my invention, what I claim is:—

1. In the manufacture of roofing tiles, a mold adapted to form a plurality of tiles at one operation, and means movable across the top of said mold for dividing up the molded tiling before removal from said mold.

2. In the manufacture of roofing tiles, a composite mold comprising a bottom plate, end closures carried by said bottom plate, and parallel guides between which said bottom plate can be fitted, said guides constituting side closures.

3. In the manufacture of roofing tiles, the combination of a mold-support, parallel guides secured upon said support, a molding pallet adapted to be inserted between said guides, raised surfaces carried by the ends of said molding pallet, and means for arresting the entrance of said pallet between said guides when said raised surfaces are level with said guides.

4. In the manufacture of roofing tiles, a molding pallet comprising a stamped metal plate, of length corresponding to the aggre-

gate width of a plurality of tiles, said plate having transverse impressions adapted to form hollows in the molded tiles, raised surfaces at the ends of said plate, and reinforcing members extending along said plate on the opposite face to said raised surfaces.

5. In the manufacture of roofing tiles, the combination of a mold having an undivided interior space of length corresponding to the aggregate width of a plurality of tiles, a support for said mold, and means for periodically lifting and lowering the opposite ends alternately of said mold from and to said support to cause settling of the material in said mold, said lifting and lowering means allowing both ends of said mold to rest upon said support between successive periods of lifting and lowering.

6. In the manufacture of roofing tiles, the combination of a mold-support, a pair of parallel guides resting upon said support, means for locating said guides upon said support while permitting them to be lifted therefrom, cross-braces connecting said guides, a multiple-tile molding pallet adapted to be fitted between said guides, means for closing the ends and sides of the mold of which said pallet forms the bottom, a cam-shaft extending longitudinally beneath said mold, and a pair of cams upon said cam-shaft, said cams alternately raising the opposite ends of said guides and mold to cause settling of the material in said mold.

7. In the manufacture of roofing tiles, the combination of a multiple-tile mold, a color-box for distributing coloring matter upon the molded tiling, and knives carried by the underside of said color box, said knives serving to divide up the molded tiling into sections when said color box is moved into operative position above said mold.

8. In the manufacture of roofing tiles, a mold for lengths of tiling corresponding to a plurality of single tiles, comprising a pair of parallel guide rails, a pallet plate adapted to fit down between said rails, and raised surfaces carried by the ends of said pallet, the height of said surfaces above said pallet corresponding to the depth of said pallet below the top edges of said rails and to the thickness of the tiling to be molded.

9. In the manufacture of roofing tiles, a mold for lengths of tiling corresponding to a plurality of single tiles, comprising a pair of parallel guide rails, cross-braces connecting said rails at a fixed distance apart, a pallet plate adapted to fit between said rails, means carried by said rails for limiting the entrance of said pallet between said rails, and raised surfaces carried by the ends of said pallet, the height of said surfaces above said pallet corresponding to the depth of said pallet below the top edges of said rails when said entrance-limiting means operate.

10. In the manufacture of roofing tiles, a molding pallet comprising a stamped metal plate of length corresponding to the aggregate width of a plurality of tiles, means for reinforcing said plate both longitudinally and transversely, said reinforcing means including transverse raised surfaces at the ends of said plate, spacer blocks beneath the ends of said plate, and complementary means upon 10 the upper surfaces of the ends of said plate and the lower surfaces of said spacer blocks for locating one pallet plate upon another when stacked.

11. In the manufacture of roofing tiles, a molding pallet comprising a stamped metal plate of length corresponding to the aggregate width of a plurality of tiles, said plate having transverse impressions adapted to form hollows in the molded tiles, raised surfaces at the ends of said plate, and a cranked flange extending at intervals along one edge of said plate, the interruptions in said flange corresponding to the lines of division between individual tiles.

12. In the manufacture of roofing tiles, a molding pallet comprising a stamped metal plate of length corresponding to the aggregate width of a plurality of tiles, said plate having transverse impressions adapted to form hollows in the molded tiles, raised surfaces at the ends of said plate, means for forming projections at the heads of the tiles along one edge of said plate, and means for forming nailing holes adjacent to said projections.

13. In the manufacture of roofing tiles, a mold for lengths of tiling corresponding to a plurality of single tiles, comprising a pair of parallel guide rails, cross-braces connecting said rails at a fixed distance apart, a pallet plate adapted to fit between said rails, means carried by said rails for limiting the entrance of said pallet between said rails, a cranked flange extending along one edge of said plate, said plate having a longitudinal series of apertures adjacent to said cranked flange, and said apertures adapted to fit over vertical members carried by said entrance

limiting means, said vertical members forming nailing holes through the molded tiles.

14. In the manufacture of roofing tiles, a mold comprising a transversely curved pallet plate, raised surfaces of similar curvature extending across the ends and middle of said plate, and parallel guides between which said plate can be fitted, said raised surfaces and guides delimiting at their top edges a transversely curved area to which said mold can be leveled off.

15. In the manufacture of roofing tiles, a molding pallet of length corresponding to the aggregate width of a plurality of tiles, and means for reinforcing said plate both longitudinally and transversely, said reinforcing means including a cranked flange, said flange extending along one edge of said plate with a central interruption corresponding to a line of division between individual tiles.

16. In the manufacture of roofing tiles, a molding pallet of length corresponding to the aggregate width of a plurality of tiles, and means for reinforcing said plate both longitudinally and transversely, said reinforcing means including a cranked flange extending at intervals along one edge of said plate, the interruptions in said cranked flange corresponding to the position of the transverse edges of individual tiles.

17. In the manufacture of roofing tiles, a molding pallet of length corresponding to the aggregate width of a plurality of tiles, and means for reinforcing said plate both longitudinally and transversely, said reinforcing means including a cranked flange extending at intervals along one edge of said plate, the interruptions in said cranked flange comprising surfaces co-planar with the body of the plate, said co-planar surfaces being connected to said cranked flange by oblique walls.

In testimony whereof I hereunto affix my signature.

FREDERICK ALFRED WILSON.
